(57) **CLAIM**

The ornamental design for a work apron, as shown and described.

DESCRIPTION

FIG. 1 is a front perspective view of the work apron showing the present design.

FIG. 2 is a front view thereof.

FIG. 3 is a rear view thereof.

FIG. 4 is right side view thereof.

FIG. 5 is a left side view thereof.

FIG. 6 is a top view thereof.

FIG. 7 is a bottom view thereof.

FIG. 8 is a front view thereof shown as worn by a user.

FIG. 9 is a front perspective view of a second embodiment of the work apron.

FIG. 10 is a front view thereof.

FIG. 11 is a rear view thereof.

FIG. 12 is right side view thereof.

FIG. 13 is a left side view thereof.

FIG. 14 is a top view thereof.

FIG. 15 is a bottom view thereof; and,

FIG. 16 is a front view thereof shown as worn by a user. The portions of the design shown in broken lines being for the purpose of illustrating environment only and form no part of the claimed design.

1 Claim, 12 Drawing Sheets
